UNITED STATES PATENT OFFICE.

JOHN W. MCCREA, OF NEW YORK, N. Y.

DESIGN FOR A HYDROCARBON-LAMP.

SPECIFICATION forming part of Design No. 34,505, dated May 14, 1901.

Application filed April 20, 1901. Serial No. 56,770. Term of patent 7 years.

To all whom it may concern:

Be it known that I, JOHN W. MCCREA, a citizen of the United States, and a resident of the city of New York, borough of Manhattan, in the county and State of New York, have invented and produced a new and original Design for a Hydrocarbon-Lamp, of which the following is a description, reference being had to the accompanying drawing, forming a part thereof, in which is represented a side elevation of a hydrocarbon-lamp embodying the features of my design.

The essential features of the design consist in the spherical body A of the lamp and curved arms B, which extend from opposite sides of the lamp, approaching one another at a point above the body A of the lamp, and in a tubular member C, which apparently connects the upper ends of the side arms B, the upper tubular member bearing a cup extension at one of its ends.

The essential features of the design further consist in the tubular extension D,

which projects from the outer face of the upper portion of one of the curved side arms B, 25 the extension D terminating in what appears to be a disk-handle, together with an arched ornament located above the curved arms and decorated with the representation of an eagle.

The minor features of the design consists 30 in the scroll formation of the arched ornament and in a swinging cap represented as pendent from the arched portion of the ornament.

Having thus described my invention, I 35 claim as new and desire to secure by Letters Patent—

The design for a hydrocarbon-lamp herein shown and described.

In testimony whereof I have signed my 40 name to this specification in the presence of two subscribing witnesses.

JOHN W. MCCREA.
